UNITED STATES PATENT OFFICE.

FLOYD STEWART TEETSEL, OF ALBANY, NEW YORK.

TYPEWRITER DESK.

Application filed January 21, 1926. Serial No. 82,821.

This invention relates to typewriter desks, the primary object of the invention being to provide a typewriter desk in which the typewriter supporting platform when lowered 5 and in enclosed position is in the rear portion of the desk structure so that ample knee space and leg room is provided under the desk.

A great fault with desks long in common use is that the typewriter supporting platform when in its lowered position is located so that very small space is allowed for the legs of the user of the desk, and this not only results in discomfort to the user but results in seriously disfiguring the desk by constant contact therewith.

A further object is to provide a desk which not only has this advantage but it has an improved arrangement of linkage 20 which enables the desk to be easily and quickly manipulated and securely held in either of its extreme positions of manipulation.

With these and other objects in view, the invention consists in certain novel features of construction and combinations and arrangements of parts, which will be more fully hereinafter described and pointed out in the claim.

30 In the accompanying drawings—

Figure 1 is a view in front elevation, showing my improved desk with the top down and the typewriter supporting platform in its lowered and enclosed position;

35 Figure 2 is a view in transverse section on the line 2—2 of Figure 1;

Figure 3 is a view in front elevation, similar to Figure 1, showing the position of the parts with the typewriter supporting platform in position for holding the typewriter when in use;

Figure 4 is a view in transverse section on the line 4—4 of Figure 3;

Figure 5 is a fragmentary detail view.

45 1 represents a desk which may have any suitable arrangement of drawers and spaces, and which is provided with a fixed top 2 and a movable cover 3 which fits an opening 4 in the central front portion of the fixed top 2 and which is located above the space A in the desk 1 which is adapted to accommodate the leg of the user at the desk. This space A may be central of the desk or otherwise positioned without departing from the invention.

5 represents a typewriter supporting platform to which a typewriter 6, indicated by dot and dash lines in Figure 4, may be rigidly secured in any approved manner.

It is the arrangement of linkage operatively connecting the movable cover 3 and the platform 5 which constitutes the essential feature of my invention and which will now be described in detail.

The arrangement of linkage is precisely 65 alike at both sides of the platform 5 and hence the description hereafter of one set of linkage will apply alike to both.

To the under face of the fixed desk top 2, a pair of depending angle iron brackets 7 is 70 secured, and to these brackets links 8 are pivotally connected between their ends, as shown at 9. The pivotal connection 9 is nearer one end of the links 8 than the other, as clearly shown in Figures 2 and 4, so as 75 to give the necessary throw or movement to the parts as will more fully hereinafter appear. The angle brackets 7 also function as supports for the movable cover 3 when the latter is in its closed or horizontal position, as clearly indicated in Figure 1.

The longer ends of the links 8 are connected to brackets 10 secured to the under face and forward portion of the movable cover 3. The shorter ends of the links 8 are 85 pivotally connected by short links 11 with the forward portion of platform 5, the connection being preferably at the edges of the platform, as indicated.

The platform 5 is also connected by links 90 12 with fixed brackets 13 rigidly secured to the fixed portions of the desk 1. These links 12 also connect to the side edges of platform 5 and near the rear or inner end of said platform. Links 14 pivotally connect brackets 95 15 on the under face of movable cover 3 with pivots 16 connected to bars 17 or other fixed parts of the desk 1.

I would call particular attention to the construction of the links 8 and 11. It will 100 be noted that the shorter end of link 8 extends beyond the pivotal connection 9 between said link 8 and the link 11, and that this end of the link 8 is provided with a laterally projecting pin or lug 18 which is 105 adapted to engage in a recess 19 in link 11 when said links are moved into substantial alinement, as indicated in Figure 4, and limit any further pivotal movement in one direction so that when the platform 5 is in its 110

horizontal position, as shown in Figure 4, there will be no tendency to the downward movement of said platform.

The operation is as follows:

- 5 Figure 2 illustrates the cover 3 in horizontal position so that it constitutes a part of the desk top. This view also illustrates the platform 5 in its enclosed position, and it will be noted that when in this position the platform 5 is disposed an appreciable distance from the front of the desk 1 so that there is ample leg room for the user of the desk. This positioning of the platform is due to the arrangement of linkage which has 10 been described and the operation of which will now be explained. To bring the platform 5 from the position shown in Figure 2 to that shown in Figure 4, the operation is as follows: The front end of the cover 3 is forced upwardly and rearwardly. This causes the link 8 to swing on its pivot 9 and through the medium of the link 11 to force the platform 5 upwardly and forwardly, the extremity of this movement being stopped 15 when the pin 18 is in the notch 19. The direction or path of this movement of the platform 5 is controlled by the swinging movement of the links 12. To return the platform 5 to its lowered and inward position the cover 3 is drawn upwardly, imparting movement to the links 8 and 11 to swing the platform 5 to the position shown in 20 Figure 4. It is of course to be understood 25 30 35

that the several links are arranged in different planes so that they do not engage each other in a manner which would interfere with the operation above described, and this is illustrated in Figure 3 of the drawing.

Various slight changes and alterations 40 might be made in the general form of the parts described without departing from the invention and hence I do not limit myself to the precise details set forth but consider myself at liberty to make such slight changes 45 and alterations as fairly fall within the spirit and scope of the appended claim.

I claim:

The combination with a desk having an 50 opening in its top, a cover normally located in said opening and a typewriter supporting platform normally below the cover, of levers pivotally connected between their ends to fixed parts of the desk, and at their upper 55 ends pivotally connected to the forward portions of the cover, said levers at their lower ends connected by links with the forward portions of the platform, links connecting the rear portions of the platform with fixed parts of the desk below the normal position 60 of the platform, and other links connecting the rear portions of the cover with fixed portions of the desk below the normal position of the platform.

FLOYD STEWART TEETSEL.
